HANDBAG

Aaron Landis, Elizabeth, N. J.

Application April 3, 1936, Serial No. 72,458

5 Claims. (Cl. 150—28)

This invention relates to portable receptacles and has particular reference to devices such as handbags and removable covers therefor.

One object of this invention is to provide a device of the character described including a removable cover having such improved association with a bag that the cover can be mounted thereon by contractile means and securely held in a neat and relatively inconspicuous manner.

10 Another object of the invention is to furnish a device of the nature set forth comprising a bag and a removable cover in improved coordination such that a two piece cover can be employed, which is not only especially easy to launder, but the parts of which are thus particularly simple to manufacture; and where the parts are duplicates of each other, the cost of manufacture held to a minimum and assembling with the bag accomplished with maximum facility.

20 Another object of the invention is to construct a device of the type mentioned wherein the cover includes separate parts in such improved relation to each other and to the foundation bag that the angle of positioning of at least one of the parts can be varied to produce different relations of the designs of the different parts.

Another object of the invention is the provision of a device of the class alluded to having relatively few and simple parts, and which is inexpensive to manufacture and assemble, neat and compact in appearance, consuming a minimum of material, especially adapted for quantity production, reliable in use, capable of varied applications and having qualities of inherent durability and interchangeability in use and in appearance.

Other objects and advantages of the invention will become apparent as the specification proceeds.

40 With the aforesaid objects in view, the invention consists in the novel combinations and arrangements of parts hereinafter described in their preferred embodiments, pointed out in the subjoined claims, and illustrated in the annexed drawing, wherein like parts are designated by the same reference characters throughout the several views.

In the drawing:

50 Figure 1 is an isometric view in side elevation showing a device embodying the invention.

Fig. 2 is a view in side elevation of a device of modified configuration.

Fig. 3 is a vertical sectional view taken on the line 3—3 of Fig. 1.

Fig. 3a is a view in end elevation of the foundation bag.

Fig. 4 is a vertical sectional view taken on the line 4—4 of Fig. 3.

Fig. 5 is a central sectional view of the cover 5 separated from the foundation bag.

Fig. 6 shows a cover section in course of being reversed.

Fig. 7 is a schematic view of a pair of cover sections showing different design coordinations 10' that can be produced by rotating or angularly moving a cover section.

Fig. 8 is a sectional view of a cover showing sections partially interconnected.

Fig. 9 is a view in elevation of a cover section 15 that can be used with foundation bags of different configuration.

Fig. 10 is a sectional view thereof, taken on the line 10—10 of Fig. 9.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

Referring in detail to the drawing, 11 denotes a device embodying the invention. The same may include a foundation bag 12 and a removable cover 13 therefor.

The cover 13 comprises a pair of sections 14 35 that may be duplicates of each other, if necessary. Each cover section may have a wall 15 and a contractile marginal portion 16 provided with contracting means 17, such as a rubber elastic, spring, drawstring or the like, disposed, for 40 instance, in a marginal hem 18 of each section.

Heretofore a removable handbag cover has never been made with its outer wall of separate pieces, whereby certain advantages herein mentioned are attained. Since a handbag cover must 45 be especially neat and attractive, it has never been feasible heretofore to use a cover consisting of separate or substantially separate outer pieces.

While the preferred form of the invention finds 50 embodiment in part in an element as simple as that shown at 14, this is made possible by a novel and improved coordination of the bag with the cover. For instance, the bag includes a pair of spaced or parallel side walls 19 interconnected 55

- by an intermediate or marginal wall or gusset 20, which may provide a bag mouth closed as by a slide fastener 21, between the side walls 19; and desirably a handle 22 can be suitably connected 5 to the gusset as at the ends of the slide fastener. The distinctive coordinating feature of the foundation bag is that the gusset or wall 20 is within the confines of the outer edges 24 of the foundation bag, or in other words, includes a portion 10 extending inward of the outer edges 24 along the plane of the bag or the side walls thereof. Preferably, this gusset is relatively continuous to thus afford a relatively continuous concavity 24a, extending, for example, along the top, ends and 15 bottom of the bag. By the same token, the edge portions 24 of the side walls 19 afford relatively continuous projections or ridges, that may be unobstructed throughout. Thus the walls 15 of the cover sections 14 overlie the side walls 19, 20 with the marginal portions 16 extending inward over the side wall edges 24. Hence the contractile portions 16 together with the contracting means are received in the said concavity, that is, 25 within the external gusset region, and in any event, so as to be concealed between the opposed edge portions of the edges 24 of the side walls 19. By stiffening the side walls 19 or the edge portions 24 thereof, a taut and neat disposition of the cover is assured.
- 30 Thus it will be seen that the device 11 is neat, simple and well adapted to quantity production. The foundation bag may be a simple conventional type. Each cover section is individually removable mounted as described, can be readily 35 laundered, and may be reversible. One or both sections may be reversed. If the bag 11 is circular, one of the cover sections can be rotated for a desired design relation to the other section.
- In Fig. 2 is shown a bag 25 which is exactly like that at 11, except that it is of elongated or 40 oblong shape. Here also the cover sections 26 are successfully used and can be applied at different 90 degree angles.
- To further illustrate rotative design relations 45 that are possible with this invention, I show in Fig. 7 a set of companion cover sections such as 27, 27a laid out side by side for easy observation. One section 27 has its stripes disposed diagonally, the other section 27a, vertically. Any other relationship for attractive variability can be obtained. The cover sections 27 may be like the 50 sections 14.
- In Fig. 8 I show a modified form 28 of the cover, which may be exactly like the cover 13, except that the cover 28 is intended to illustrate 55 that the sections 29 may be interconnected at one or more points as by strips or tabs 30 disposed along or at the hems 18 to provide a one piece cover, within the scope of the invention.
- 60 In Figs. 9 and 10, I show one of a pair of duplicate cover sections 31 exactly like a section 14, except that it includes elastic crossing lines of stitching 32 formed as with an elastic thread to produce gathers 33. This cover section can be 65 applied equally well to round, square and oblong foundation bag walls, and also to such walls of different sizes, due to the give or yield in the cover section 31, by reason of the elastic 32. Normally, the gather 33 is always obtained to some 70 degree and produces a certain fluffy attractive design effect, with the cover section securely held and with the gather in a hem such as 18 fairly uniformly distributed. Obviously, the elastic stitching 32 is representative of any elastic ele-

ments in the body or side wall of the cover section.

It will be appreciated that various changes and modifications may be made in the device as shown in the drawing, and that the same is submitted in an illustrative and not in a limiting sense, the scope of the invention being defined in the following claims.

I claim:

1. A handbag including a bag body having side 10 walls positioned in relatively close relation to each other, a gusset interconnecting the side walls and providing an opening for the bag body intermediate of the side walls, the side walls each providing relatively continuous substantially stiff 15 edge portions extending along the plane of the bag body beyond the gusset, and a removable cover including a plurality of cover sections, each section comprising a wall covering a side wall of the bag body, each section comprising a relatively continuous contractible marginal portion and means for relatively uniformly contracting the marginal portion, the different marginal portions and contracting means lying relatively closely along the gusset with the sections drawn 20 comparatively taut over the side walls of the bag body and with the marginal portions thus maintained in spaced relation to said opening, and the said marginal portions being substantially concealed between the opposed edge portions of 25 the said side walls of the bag body.

2. A device including a bag having side walls and a marginal wall interconnecting the same, the marginal wall extending along the edges of the side walls and having a central region spaced inward of the edges of the side walls in the direction of the plane of said walls, the edges of each of the side walls being relatively stiff and substantially continuous throughout the major extent of the bag, and a removable cover comprising 35 a plurality of separate cover sections, each section having a wall exteriorly overlying a side wall of the bag, each section having a continuous contractible marginal means and means for contracting the same, the contractible portions and contracting means of the different sections being received and substantially concealed in the concavity provided along the said marginal wall and inward of the edge portions of the side walls, with the contracting means holding the cover 40 sections on the bag and causing the marginal cover portions to snugly fittingly engage the edge 45 portions of the side walls of the bag.

3. A device including a bag having side walls having relatively stiff edges, an interconnecting 55 wall between the side walls disposed so as to leave the edge portions of the side walls projecting beyond the interconnecting wall substantially throughout the bag, to thus provide a concavity extending along the edge of the bag, a cover comprising a plurality of separate reversible cover sections, each having a one piece wall overlying a side wall of the bag and each having a continuous integral contractible portion, the contractible portions of the cover sections passing over 60 the edge portions of the side walls of the bag into said concavity and being concealed therein, and contracting means in said concavity for relatively uniformly individually contracting the contractible means in the concavity to cause the 65 cover sections to be tautly removably secured to the bag.

4. A device including a bag having side walls in relatively closely spaced relation to each other and a marginal wall interconnecting the same, 70

the marginal wall extending along the edges of the side walls and having a central region spaced inward of the edges of the side walls in the direction of the plane of said walls, said central region having a closable opening for the bag, the edges of each of the side walls being relatively stiff and substantially continuous throughout the major extent of the bag, and a removable cover comprising a plurality of separate cover sections, each section having a one piece wall exteriorly overlying a side wall of the bag, each section having an integral contractile continuous marginal means and means for contracting the same, the contractile portions and contracting means of the different sections being received and substantially concealed in the concavity provided along the said marginal wall and inward of the edge portions of the side walls and in laterally spaced relation to said opening, with the contracting means holding the cover sections on the bag and causing the marginal cover portions to snug-

ly fittingly engage the edge portions of the side walls of the bag, and the cover sections being rotatable through predetermined angles relative to their respective side walls to obtain different design relations as between the different cover sections. 5

5. A portable receptacle including a bag having spaced side walls, a cover for the bag, comprising separate cover sections covering the side walls and carrying designs, the side walls and 10 the respective cover sections having releasably interengaging marginal means, each marginal means including a contractile marginal portion forming a part of a cover section and engaging an adjacent marginal portion of a side wall of the 15 bag, at least one of the marginal means being so uniform as to permit its corresponding section to be secured to its respective wall at different angles to thus produce different relations in the designs carried by the different cover sections. 20

AARON LANDIS.
